DIFFUSER FOR LIQUID AERATION OR THE LIKE

Billy S. Washburn, St. Charles, Ill., assignor to Bowser, Inc., Chicago, Ill., a corporation of Indiana

Filed Dec. 4, 1967, Ser. No. 9,615

Term of patent 14 years

U.S. Cl. D23—4
Int. Cl. D23—01

FIG. 1

FIG. 2 is a side elevational view thereof, the other sides being substantially the same in appearance.

I claim:

The ornamental design for a diffuser for liquid aeration or the like, as substantially shown and described.
